UNITED STATES PATENT OFFICE.

CARL E. BROWN, OF COLUMBUS, OHIO.

PIANO PLAYER.

Application filed October 11, 1923. Serial No. 667,813.

My invention relates to devices employed in connection with electro-magnetically operated pianos for imparting an operating blow to the piano mechanism, and for varying the tonal quality of the blow imparted.

In the device shown I have confined myself to loud and soft adjustment without reference to intermediate adjustment, and it will be understood that I contemplate the use of my invention for imparting all degrees of tonal quality to blows struck upon the key levers or other hammer operating parts of player pianos.

It should be noted also, that while my invention is particularly applicable to electro-magnetically operated player pianos, that it has a wider application to any player piano or expression device.

The operation of an electro-magnet is such that the nearer the armature gets to the magnet, the stronger the pull thereon. Thus in my structure wherein I employ electro-magnets to operate the piano, I particularly take this feature into consideration. One of my objects is to mechanically oppose the action of the armature of an electro-magnet in such a way that the opposition becomes stronger as the armature approaches its seat. Another object of my invention is to control the expression changing device electro-magnetically, and to that end to provide a mechanism which does not require any appreciable power to operate it. Another object of my invention is to provide a mechanical expression changing device which is simple in construction and can be applied to individual note striking devices, or to the entire key board operating mechanism, as desired.

The above objects and other advantages to be noted, I accomplish by that certain construction and arrangements of parts to be hereinafter more specifically pointed out and claimed.

In the drawings, Figure 1 is a side elevation of an individual key striking device for electro-magnetically operated pianos, showing the essentials of my invention. Figure 2 is a bottom plan view of a portion of the structure showing the connection of the spring and the guard plate with relation to the striker rod.

I have indicated a piano key at 1, and have shown my mechanism as acting on this

key. It should be understood that where the player mechanism is built into the piano, that some other member than the forward or exposed portion of the piano key will be directly acted upon.

I have shown a sketch of a simplified form of tracker mechanism and stencil roll in order to make a clear disclosure of the method of operation of my device although these elements do not concern the present invention.

I have shown a magnet 2, which has an armature 3, connected to the note striking finger 4, by a rod 5. The rod has an adjustable nut 6 at its end where it protrudes through finger 4, whereby the pulling down of the armature toward the magnet will exert a pull upon the finger, causing it to strike the key. The finger is pivoted at 6^a on the frame or mounting portion 7 of the mechanism, and has an adjustable contact screw 8 therein. The armature may be faced with rubber as at 3^a to cushion the stroke, eliminate noise and cut down any residual magnetism drag.

Mounted on the portion 9 of the machine frame, is a spring 10, which preferably is shaped as shown, the essential being that in this form of device the spring be a leaf spring. The rod 5 passes through a hole 10^c in the spring 10. The free end of the spring 10 contacts with the adjustable screw 8, thereby tending to force the finger 4 upwardly and thus allowing the piano key to assume its normal position, in opposition to the movement of the armature 3 of the operating magnet. The spring thus acts to free the key after each blow, and also to lift the armature of the magnet away therefrom, holding the parts ready for successive operations.

The action of the spring is to oppose the pull of the armature more and more strongly as the armature approaches its fully seated position. This as has been pointed out, corresponds to the action of the armature itself, so that while providing a sure return of the parts to normal position after each operation, there will not be enough interference with the movement initiated by the electro-magnet at its inception, to result in a failure of a playing stroke.

In order to effect the change of tonal quality of the blow of the playing finger on

the key, I provide means for changing the effective length of the leaf spring so that by making it shorter, I am able to increase the resistance to the force opposing the magnet.

5 To this end I have shown the spring as being shaped with a portion 10^a, which is secured to the frame and then slants upwardly, the spring being then bent into a line of fold at 10^b. The electro-magnet 11 is provided 10 having an armature 12, the rod 13 of which passes through a hole 13^b of larger diameter than rod in the frame part 9, as a support and is pivotally connected to a lever 13^a. The lever 13^a may be pivoted on a rod 14, and have also a connecting rod 15, extending to another electro-magnet armature 15^b, or to a spring.

I mount over the spring portion 10^a a guard plate 16, which extends along the portion 10^a of the spring to the bend at 10^b. The ear 16^a on this plate 16 may be provided to act as a side guide for the finger 4 and the rod 5 passes through a hole 16^b in this plate.

25 I have shown a sketch of a tracker mechanism 16 in which the stencilled roll 17 passes over the contact points 18 and 19 which connect with the magnets 11 and 11^a through which control of the lever 13^a is effected. The note playing magnet 2 is shown as being controlled from the contact point 20. The contact points 21 and 22 represent points for other notes on the key board. It is of course only a diagrammatic drawing of 30 a tracker mechanism as a plurality of note contact points would be used in the actual construction of such a device. Contact is made through the arm 23 on which is attached the contact fingers, which complete 40 the circuit when the stencilled apertures 25 expose the contact points.

As so constructed, the energizing of the circuit through magnet 11, will pull the lever 13^a to the position shown in the drawings, of 45 touching the spring at 10^b, in which way the effective length of the spring 10 is changed, so that when the magnet 2 is energized, and a pull applied to the striking finger, this pull will be opposed by the end 50 only of the spring 10 since the portion 10^a cannot bulge upwardly due to the guard plate 16. The energizing of a magnet whose armature is connected to the connecting rod 15 will result in the lever 13^a being pulled 55 in a position entirely out of the way of the spring 10. When the lever is so positioned, the spring will give the less resistance to the movement of the armature 3, than in the instance where a portion of its movement is 60 prevented by the combination of the guard plate 16 and said lever.

The lever 13^a instead of being a relatively narrow bar, could be a plate extending along beneath a series of springs 10, one 65 spring for each key striking finger. The

shifting of the plate would then change the spring opposition for all the key fingers at one time, and using a limited number of magnets 11.

As stated I have not attempted to show 70 mechanism for effecting the change of length of the magnet opposing springs, in more than two positions. However, I wish to cover the use of a device which will effect the spring length in any number of positions, 75 more than one.

Having thus described my invention, what I claim as new and desire to secure by Letters Patent, is:—

1. A device of the character described, 80 comprising a member for imparting a blow to a piano action, means for operating the member, a spring connected to oppose the operating direction of said blow, and means for changing the effective length of said 85 spring during the operation of the piano, thereby changing the force of the blow.

2. A device of the character described, comprising a member for imparting a blow 90 to a piano action, means for operating the 90 said member, a spring connected to oppose the operating direction of said blow, and an electro-magnetically controlled means for changing the effective length of said spring 95 during the operation of the piano, thereby changing the force of the blow.

3. A device of the character described, comprising a member for imparting a blow to a piano action, an electro-magnetic means 100 for operating the same member, a spring connected to oppose the operating direction of said blow, and an electro-magnetically controlled means for changing the effective length of said spring 105 during the operation of the piano, thereby changing the force of the blow.

4. In combination a pivotally mounted striking finger for a key lever of a piano, an electro-magnet having connection with the same for moving it to impart a blow to the key lever, a leaf spring engaging the finger, and opposing its striking motion, and a member movable to position to engage said spring between its points of mounting and of lever engagement, thereby changing its effective length, as opposing the force of 110 said electro-magnet.

5. A device of the character described, comprising a member for imparting a blow 115 to a piano action, means for operating the member, a leaf spring mounted so as to engage the said member, and a lever electro-magnetically controlled, and adapted to take a position of engagement with the said leaf 120 spring between its attachment point and its engagement point with the said member, for the purpose described.

6. A device of the character described, comprising a member for imparting a blow 125 to a piano action, means for operating the

member, a leaf spring having an intermediate line of partial bend, and engaging the said member at one end, and a fixed portion of the device at another, a guard lying along the spring from its fixed mounting to a point adjacent the line of bend, and a lever controllable for momentary movement, to po-

sitions adjacent the spring at the line of bend opposite the end of the guard plate, and to positions out of opposition to the spring movement, said spring being so arranged as to oppose motions of the member in imparting its blow to the piano action. 10
